UNITED STATES PATENT OFFICE.

JOHN S. NOEL, OF GRAND RAPIDS, MICHIGAN, ASSIGNOR TO DON DEVENDORF, OF GRAND RAPIDS, MICHIGAN.

KEROSENE BURNER.

Application filed September 10, 1919. Serial No. 322,951.

To all whom it may concern:

Be it known that I, JOHN S. NOEL, a citizen of the United States of America, residing at Grand Rapids, in the county of Kent 5 and State of Michigan, have invented certain new and useful Improvements in Kerosene Burners; and I do hereby declare the following to be a full, clear, and exact description of the invention, such as will enable others skilled in the art to which it app pertains to make and use the same.

This invention relates to improvements in kerosene generators and burners. It is an object and purpose of the invention to provide a construction in which kerosene may be used as a fuel and generated into a gas for a burner, the construction being applied to stoves, furnaces or the like, in the present case, particularly to stoves or ranges 15 used for cooking purposes. A further object of the invention is to provide a novel generating, mixing and storage housing for gas which is generated for the burners, the same containing a reservoir, compartment

20 in which a relatively large amount of generated gas fuel mixed with air may be contained and from which the gas passes directly to the burners where it is consumed. A still further object of the invention is to provide a device of this character in which a plurality of burners may be connected with and receive generated gas from said reservoir compartment and any burner or burners which it is not desired to use may be 25 cut off from said reservoir, use being made of a very simple and easily operated control for effecting this purpose. A still further object of the invention resides in a novel generator member such that the heavier 30 hydro-carbon oils, as kerosene and the like, may be completely vaporized, mixed with air and carried a considerable distance before it comes to the reservoir, thus avoiding tendency to back-fire which may occur 35

40 should the parts where the mixed air and fuel is burned, be close to the air inlet. A still further object of the invention is to provide a novel construction of generator tube which is equipped with devices on the 45 inside thereof which may be used to remove any carbon deposits which may form and which is an aid to generation in that it disseminates heat throughout liquid fuel within the tube and helps maintain it at a high 50

degree of temperature prior to its injection 55 into the mixing chamber of the device.

All of these features together with many others not specifically stated at this time, will appear fully and in detail in the following description, taken in connection with the 60 accompanying drawings, in which:

Fig. 1 is a plan view of the complete generator and burner.

Fig. 2 is a partial plan and sectional view of the burner generator tube, and Fig. 2^a is 65 a detail view of a disk 39.

Fig. 3 is a longitudinal horizontal section taken through the burner housing or casing, the generator tube being shown in plan.

Fig. 4 is a vertical section taken transversely through the burner and generator 70 at a point substantially half-way between its ends.

Fig. 5 is a fragmentary section taken transversely of the device at the rear lower 75 portion thereof and showing the means for detachably holding the generator tube in place.

Fig. 6 is a longitudinal vertical section through the burner taken near the front side 80 thereof.

Fig. 7 is a plan view of the under part of one of the gas burners used.

Fig. 8 is a plan view of the shut-off valve, one of which is used with each of the gas 85 burners, and

Fig. 9 is a fragmentary enlarged vertical section taken in the upper front corner of the burner and showing the way in which the valve may shut off gas which ordinarily 90 passes to a gas burner.

Like reference characters refer to like parts in the different figures of the drawing.

In the construction, a hollow casting or housing is provided having front and rear 95 sides 1 and 2, a bottom 3 and a top 4. Between the top and bottom a horizontal partition 5 is located and below said partition between the sides 1 and 2, a vertical partition 6 is positioned. This divides the casting 100 into three compartments 7, 8 and 9, each of the lower compartments being about one-half the capacity of the upper compartment. The housing is completed by ends 10 and 11, supporting feet 12 and a trough 13 which is located in front of and at the lower part of the housing. This trough lies along side 105 of the side 1 for a distance and is curved par-

tially around the end 11 as shown. At one end of the trough and near the curved portion thereof, members 14 each having a slot 15 are cast integral with and project from the side 1, the slots being located at a distance above the trough for a purpose which will later appear. In the side 1 at the same height as the slots 15 a row of small holes 16 are made, being positioned closely together and extending practically the entire length of the trough.

An opening 17 is made in the vertical partition 6 near the end 10. An opening 18 is made in the bottom 3 between the partition 6 and the side 2 and near the end 11 of the housing. The bottom 3 between partition 6 and side 2 inclines downwardly from the end 10 to the opening 18 as indicated at 3^a. The partition 5 between compartments 7 and 8 and near the end 11 of the casting, is also provided with an opening 19 which is slightly larger in area than opening 17, said opening 17 likewise being slightly larger in area than the opening 18.

In the top 4 of the casting, three openings 20 are made. Covering each of two of them, those adjacent the ends of the casting is a housing 21 integral with which is the lower part 22 of a regular gas burner. The burner is completed by an upper member 23 radially slotted in the usual manner, as shown. The central opening 20 is likewise covered by a housing 24 from which a conduit 25 extends, the same being bent down to pass back of the rear side 2 and connected at its lower end with a horizontal tube 26 closed at its ends but provided with a plurality of slots 27 in its rear side the same being spaced apart but made at close intervals. In each of the housings 21 and 24 a shut-off valve 28 of the shape shown in Fig. 8, is located, one end having a depending handle member 29 which passes through and is pivotally mounted in a horizontally extending ledge 30 cast integral with the casting described. By turning a handle 29 its connected member 28 may be moved to cover or uncover the adjacent opening 20 which is located under the housing in which the member 28 is mounted.

A member 31 is inserted through the end 11 and into the compartment 9 directly above the opening 18. The inner end of this member is bored out and threaded to receive a nozzle 32 which has an orifice, the same being more or less opened and closed by an adjustable needle valve 33 operated by handle 33^a. A generator tube 34 has one end connected with the member 31 to communicate therewith and from thence curves around the end 11 and lies along side of the side 1, being received in the slots 15 of the parts 14, heretofore described, and being spaced a short distance from the side and end of the casting and positioned so that the

openings 16 are in the same horizontal plane with the center line of the tube. At its free end the tube 34 may be engaged by a hook 35 pivotally mounted on the end of the trough 13, as shown in Fig. 5, and a coupling 36 may be used for connecting the tube in any suitable manner with a tank or other container which holds a liquid fuel, such as kerosene, under pressure.

The trough 13 at the end nearest the member 31, is formed with an integral enlargement 13^a into which a fuel, such as wood or denatured alcohol, may be entered to more or less fill the trough. Within the tube 44 a wire 37 is positioned, the same being wound into a series of coils which are strengthened and reinforced by a central wire 38 running the entire length of the coil as shown in Fig. 2. The coil wire 37 extends the entire length of the tube 34 and may be readily inserted or removed from the tube whenever the coupling 36 is removed. If desired one or more disks 39 with openings therethrough may be interposed in the length of the wire coil.

In operation the trough 13 is filled to any desired height with wood alcohol or the like and the fuel is entered into the tube 34 after which the alcohol is ignited. The needle valve 33 may be moved to close the orifice in the nozzle 32. The alcohol is allowed to burn until the fuel within the tube is heated to a very high degree of temperature such that, when exposed to the air it will vaporize and mix therewith. When the tube and fuel contained therein has been thoroughly heated the needle valve may be opened by operating the handle 33^a shown in Fig. 2, and the fuel allowed to escape under pressure through the orifice in nozzle 32. It receives air through the opening 18 and mixes therewith passing through the opening 17 into the compartment 8 where a certain portion of it passes through the opening 16 and is ignited by the burning alcohol while the remainder passes to upper compartment or reservoir 7 from which it may pass through any uncovered opening 20 to the burner which is associated therewith. The amount of fuel for one, two or three burners may be regulated by the regulation of the needle 33. Any fuel which is not vaporized will run down the inclined floor 3^a of the mixing compartment 9 to the air inlet opening 18.

This construction may be placed in the fire box of a cook stove and the two burners having upper plates 23 may be used for heating the upper removable griddles while the rear burner may be used to heat the oven. Any number of the burners may be used and any burner which is not to be used may have its fuel supply cut off very quickly and easily by moving valve 28 to shutting-off position. The mixed fuel and air passes a considerable distance before it reaches any

of the burners and is thoroughly mixed. The generation of the liquid into a gas takes place at a point considerable below where the gas is burned and there is little or no danger of back-fire. When the fuel has once been heated by the alcohol the continuation of generation by heating the tube comes through the gas which passes out of openings 16 and is burned directly against the inner side of the tube 34. The coil wire 37 with disks 39 aids this generation as it is kept at a high degree of temperature at all times and the fuel entering the tube has to pass around this wire for the entire length of the tube and through the disks before it escapes into the compartment 9. Moreover any carbon which may deposit in the tube is easily removed on removing the wire into tube may be kept clean with little or no trouble, and the disks serve to collect any solid matter which may be in the fuel or which may deposit.

The construction described is relatively simple and has proven very successful in practice. Many variations in detail of construction may be resorted to without departing from the invention which is defined in the appended claims and I consider myself entitled to all modifications which fall within the scope of said claims.

I claim:

1. In a construction of the character described, a housing comprising parallel sides and parallel top and bottom, and ends, a horizontal partition in the housing dividing the same into upper and lower compartments, a vertical partition in the lower compartment dividing the same into two compartments, said vertical partition having an opening therein near one end of the housing and said horizontal partition having an opening near the opposite end of the housing at one side to connect one of the lower compartments with the upper compartment, and said bottom having an opening therein near the same end of the housing for entrance of air into the other of the lower compartments, a fuel inlet into the last mentioned compartment directly over the air inlet opening, means to heat the fuel before entrance into said compartment, and burners attached to the top of the housing to which mixed air and fuel in gaseous form may be carried from the upper and larger compartment, substantially as described.

2. In a device of the character described, a construction including three elongated and enclosed compartments located in parallel relation to each other, two of said compartments being located below the other compartment and being each substantially half the cross-sectional area of the upper compartment, said lower compartments having communication adjacent one end, and one of said lower compartments having com-

munication adjacent its opposite end with the upper compartment, while the other lower compartment has an air inlet opening at the same end where the first lower compartment and the upper compartment have communication, a fuel inlet into the second lower compartment directly over the air inlet opening, means to heat the fuel before entrance into the compartment and mixture with air, and gaseous fuel consuming burners connected with the upper compartment and located above the same and adapted to receive mixed air and fuel in gaseous form from the upper compartment, substantially as described.

3. A construction containing the elements defined in combination in claim 2, in which the compartment into which the fuel is entered is provided with an inclined lower wall the same sloping from the end of the compartment opposite to that at which the fuel is entered substantially the full length of the compartment to the air inlet opening, whereby any liquid fuel will run down said incline to the air inlet opening and drain from the compartment, substantially as described.

4. In a device of the character described, a hollow elongated casting provided with horizontal and vertical partitions dividing the casting into longitudinal compartments, an upper compartment and two lower compartments, said partitions having openings whereby the lower compartments are connected adjacent one end of the casting and one the upper compartment is connected with one of the lower compartments adjacent the opposite end of the casting, said other lower compartment having an air inlet opening near the end of the casting opposite that at which the lower compartments are connected, a trough positioned at one side of the casting, a tube held a short distance above the trough, means connected at one end of the trough and passing through an end of the casting directly over the air inlet opening, said means operating for the delivery of fuel from the tube into the second mentioned lower compartment, burners connected with the casting and communicating with the upper compartment to receive mixed air and fuel therefrom, and means whereby the tube may be heated by burning mixed air and fuel taken from the first lower compartment at points alongside the tube, substantially as described.

5. In a device of the character described, a generator comprising a tube, a wire formed into a plurality of consecutive relatively widely separated coils positioned lengthwise of the tube with the outer sides of the coils contacting with the tube at its inner sides, a center wire extending lengthwise of and within the coils, connected at its ends to the end coils of the coiled wire

and thereby serving to hold the coils separated, said center wire being free from contact with the coils at their inner sides, there being space for the passage of fuel 5 between the center wire and said coils.

6. In a device of the character described, a generator comprising a tube, a wire formed into a plurality of consecutive coils positioned lengthwise of the tube, said coils 10 contacting with the inner sides of the tube, a center wire extending lengthwise of and within the coiled wire and spaced therefrom, and disks provided with openings therein mounted on the center wire, substantially as and for the purposes described.

7. In a device of the character described, a generator comprising a tube, a length of wire formed into a coil inserted in the tube, the coils of the coil of wire contacting with 20 the inner sides of the tube, means disposed within and lengthwise of the coil of wire and spaced therefrom to hold the coils thereof separated, and a plurality of perforated disks located in the length of the 25 coil and transversely thereof, substantially as described.

8. In a device of the character described, a construction comprising three enclosed compartments, two of said compartments being located below the third compartment, 30 said lower compartments having communication at one end, and one of said lower compartments having communication with the third and upper compartment at the other end, said other lower compartment 35 having an air inlet opening therein at its lower side and at the end opposite to that where it communicates with the first lower compartment, means for entering fuel into the second lower compartment directly 40 above the air inlet opening, means to heat the fuel to a high degree of temperature prior to its entrance into said second compartment, burners located above the construction and communicating with the upper compartment, and means to open or close communication between any burner and said upper compartment substantially as described.

In testimony whereof I affix my signature. 50

JOHN S. NOEL.
